FIG. 5.

UNITED STATES PATENT OFFICE

2,474,803

VERTICAL SHAFT EXCAVATING APPARATUS

Alvin A. Putnam, St. Louis, Mo.

Application May 10, 1947, Serial No. 747,217

7 Claims. (Cl. 214—134)

1

This invention relates to vertical shaft excavating apparatus, and with regard to certain more specific features, to such apparatus for sinking shafts through rock and the like.

Among the several objects of the invention may be noted the provision of shaft-sinking excavating apparatus which will increase the speed and decrease the cost of driving a shaft through rock or the like; the provision of apparatus of the class described which increases the ease and safety with which the necessary mucking operations may be performed; and the provision of apparatus of the class described which will substantially increase the life of machinery used in shaft sinking operations. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a vertical section showing the apparatus of the invention applied to shaft sinking operations, the dotted lines indicating certain alternative positions of such apparatus;

Fig. 2 is a vertical section taken on line 2—2 of Fig. 1, parts being broken away as required better to illustrate the invention;

Fig. 3 is a plan view of the operating parts of Fig. 2, showing in dotted lines an alternative position of a power shovel, the surrounding shaft walls not being shown;

Fig. 4 is a fragmentary detail view of certain shovel parts; and,

Fig. 5 is a perspective view, parts being broken away.

Similar reference characters indicate corresponding parts throughout the several views of the drawings.

Referring now more particularly to Fig. 1, there is shown at numeral 1 a rock shaft which is illustrated as being sunk by means of the invention. This shaft, by way of example, is shown as of rectangular cross section; but it is to be understood that the invention may be carried out in connection with shafts of other cross sections.

As the shaft 1 is extended downward, bracing is built in as shown generally at 3. Such bracing is generally most economically constructed of wood, although other materials may be employed. It is composed of shaft timber sets, each made up of braces 5 and studdles 7. The bracing may be held in place by wedging in planks between it and the shaft, as illustrated at 9, or in any other suitable manner. The bracing is not built right down

2

to the bottom 11 of the shaft 1, but to a point 13 a suitable working distance above the bottom.

Suspended approximately below one side of the bracing 3 is an elongate traverse bar or portable support 15 of substantial extent. At suitable points this bar carries prowls 17 for skidding the bar over the side of the shaft. Each end prow carries a sheave 19 for accommodating a suspension cable 21. The latter is anchored to one side 10 of the lower end of the bracing 3 as at 23, and is then threaded through one sheave at one end of the traverse bar 15, then through the sheave at the other end of the traverse bar and then up to a power-operated hoisting drum 25 supported at the lower end of the bracing 3. By winding in and paying out cable 21 from the drum 25, the traverse bar 15 may be raised and lowered along one wall of the shaft which is being sunk. The length of the traverse bar is preferably nearly equal to one width of the shaft. Pivoted to the prowls 17 are hydraulic or air jacks 27, by means of which reactive forces may be applied to the ends of the traverse bar from suitable points in the excavation. These anchor the traverse bar at any given elevation.

The traverse bar 15 is built up into a channel section (Fig. 4) for accommodating rails 29 which act as guide supports for wheels 31 (on horizontal axes) and lateral guide rollers 33 (on vertical axes). The wheels 31 and rollers 33 movably support a carriage 35 on the traverse bar. This carriage includes an operator's seat 37 next to which are controls 41 and a power-operated drum 39. The power unit is shown at 40. The drum 39 has wrapped about it several turns of a cable 43. The ends of the cable are held by anchors 45 near the ends of the traverse bar 15. Thus if the drum 39 is rotated in one direction or another as determined from the controls 41, the carriage 35 may be made to move back and forth on the traverse bar 15. It is of course obvious that other traversing means might be substituted for the drum and cable, such as, for example, a rack and pinion drive or the like.

45 The carriage 35 includes a horizontal pivot 47 upon which is pivoted the boom 49 of a power shovel. Articulated with the boom 49 is the usual dipper stick 51 carrying a shovel 61. The shovel has an openable bottom 63 controllable in the usual way from controls 41 by an operator in the seat 37. On the dipper stick is a crowding rack 53 controlled from a pinion 55, the latter being reversibly driven through a chain drive 57 from a crowding motor 59, the latter being under control of the operator in seat 37 through said controls 41. The station for the controls 41, includes the operator's seat and is movable with the movable elements which support the boom.

At the end of the boom 49 is anchored at 65 one end of a dipper control cable 67 which passes over

the control sheaves 69 attached to the dipper end. The other end of the cable 67 wraps on a power-driven hoist drum 71, also under control of the operator in seat 37 from his controls 41.

Details of the controls 41 are not given, since these are old on known shovels and the like.

Pivoted near the outer end of the boom 49 is a sheave block 73 through which is threaded a cable 75, the latter being anchored at 77 at an elevated point and to one side of the bracing 3. The other end of the cable 75 is wrapped on a drum 79 of a power hoist 81 carried in the upper portion of the bracing 3.

Both of the hoists 25 and 81 are under control of a workman in the shaft by means of suspended rope controls 83.

From the above it will be clear that the power shovel may by means of the carriage 35 be traversed into any lateral position in the lower end of the shaft, as illustrated by the solid- and dotted-line positions in Fig. 3; also that the boom 49 and dipper stick 51 may be manipulated so that the shovel 61 will reach muck on any part of the floor of the shaft, as illustrated by the solid and dotted lines in Fig. 1, for example.

In order to hoist material picked up by the shovel 61, the bracing 3 carries two lines of vertical tracks 85 and 93 composed of pairs of channel rails for the wheels 87 of a hoist bucket 89. While the permanent main runs of the tracks 85 and 93 end at the lower end of the bracing 3 (see numeral 91), temporary portions 93 and 94 may be built down from time to time below the bracing 3 so that the bucket 89 may be brought below a raised position of the shovel 61. The bucket may traverse either run 85 or 93. The bucket 89 includes a bail 95 for suspending it from a hoisting cable 97. The double runs of track minimize the traversing movement required for the shovel when working on one side of the shaft.

It will be understood that the various power driving units mentioned may be of the type suitable for safety in the shaft being driven; for example, they may be pneumatic, hydraulic or electric, as the rules allow.

It will be seen that the reactions on the traverse bar due to the weight of the boom and shovel parts, including the shovel load, are such as normally to force the traverse bar against the side wall of the shaft, without the anchoring jacks 27. These jacks serve mainly for steadyng purposes. It will be observed that practically the entire load of the shovel and bar parts is carried by the cables 21 and 75.

The bucket 89, if desired, also provides transportation for introducing and removing personnel from the shaft.

Operation is as follows:

Assume that by means of previous operations the bottom of the shaft has been driven down to the elevation E and cleaned out. At this time the jacks 27 are relieved and the traverse bar 15 is drawn up into the dotted-line position shown in Fig. 1, which is just under the lowermost timber set. At this time the boom 49 is folded up and the dipper stick 51 is folded down (jack-knifed). This places the shovel parts in the least vulnerable positions in respect to any blast which will occur in the shaft. The bottom of the shaft is drilled and charged. The hoist bucket 89 is removed with personnel. Temporary tracks 93 may also be removed but this will not always be necessary.

The bottom is then blasted, which again deposits a layer of muck which must be removed. This

is easily accomplished by letting down the personnel in the bucket; then the traverse bar 15 to an elevation just over the upper level of the muck. It is then anchored by means of the jacks

27. The cable 75 is adjusted for the best position of the boom. The operator in the seat 37 may at will traverse the carriage 35 carrying with it the boom 49. During traverse, the sheave 73 works back and forth under the triangular loop formed by the cable 75 (note Fig. 3). The operator controls the angling and crowding of the dipper stick from the controls 41 and dumps scooped loads from the shovel 61 into the bucket 89. The latter from time to time is pulled up along the rails 93 and 85 by means of the hoisting cable 97 to be dumped above ground.

It will be understood that the timber sets above described as supports for the apparatus also have the function in many shafts of bracing the sides of the shaft in cases where the condition of the rock is not firm.

If the rock is of such good condition that it will support itself without bracing timber sets, then the supporting structure may be installed at the top of the shaft, above ground level; and as the work progresses downward, the cables 21, 75, 97 are lengthened, as already described. In such case a lifting bucket may be used requiring only the cable 97 and no tracks, or tracks may be used with only enough support to hold them in alignment. Thus the supporting structure needed for the suspended parts is supplied by the timber sets, when used; but if they are not used, then the supporting structure at the top of the shaft serves only to support the excavating apparatus. I have used as an illustrative example the case wherein the supporting structure is in, and also supports the shaft. The character of a non-shaft-bracing structure that would be used above ground will be obvious from the above description and further details will be unnecessary to those skilled in this art.

Advantages of the invention are that during the explosion the operating apparatus is retracted into a relatively safe position wherein little or no damage will be done to it. It presents a minimum projected area in the direction of the blast.

The traverse bar 15 is easily let down into the desired position and anchored. Although the length of the traverse bar may be greater than the inside length of one side of the bracing 3, during descent it can be angled into position along the diagonal of the bracing. Being shorter than the diagonal, it can readily be introduced and removed while the shovel parts are folded up. It will be noted that this requires no disassembly of the traverse bar and shovel parts. In the final anchored position of the bar it is located on a side wall where it does not interfere with any operations of the shovel 61 in connection with all of the muck on the floor of the shaft (note the lower left of Fig. 1).

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. Excavating apparatus for sinking shafts in rock and the like, comprising a supporting structure, a traverse bar adjustable suspended from the supporting structure in the space below said struc-

ture and engageable with a side of the shaft, a traversing carriage on the traverse bar, a boom pivoted on the carriage, adjustable means extending from the supporting structure for suspending the boom at a desired angle, a shovel on the boom, means controllable by an operator at the bottom of the shaft for controlling the elevation of the traverse bar and also the boom suspension, means controllable by an operator on the carriage for traversing the carriage on the traverse bar and for controlling the operation of the shovel on the boom, the adjustable boom support comprising a sheave on the boom and a cable anchored toward one side of the shaft and passing through the sheave to a winding reel towards the other side of the shaft, whereby when the carriage is traversed the boom support will be effective in any traversed position of the boom.

2. Excavating apparatus for sinking shafts in rock and the like, comprising a supporting structure, a traverse bar adjustably suspended from the supporting structure in the space below said structure and engageable with a side of the shaft, a traversing carriage on the traverse bar, a boom pivoted on the carriage, adjustable suspension means extending from the supporting structure for suspending the boom at a desired angle, a dipper shovel on the boom, means controllable by an operator at the bottom of the shaft for controlling the elevation of the traverse bar and also the boom suspension, means controllable by an operator on the carriage for traversing the carriage on the traverse bar and for controlling the operation of the shovel on the boom, the dipper shovel and boom being adapted to be vertically jackknifed with respect to the traverse bar, the adjustable suspension means for the traverse bar being adapted to lift the bar to a location to place the jackknifed elements in a safe elevated position when the bottom of the shaft is to be blasted.

3. Excavating apparatus for sinking shafts in rock and the like, comprising a hollow brace structure extending in a shaft to a point short of its bottom, a traverse bar adjustably suspended from the brace structure in the space below said structure and engageable with a side of the shaft, a traversing carriage on the traverse bar, a shovel boom pivoted on the carriage, adjustable suspension means extending from the brace structure for suspending the boom at a desired angle, a dipper shovel on the boom, means controllable by an operator at the bottom of the shaft for controlling the elevation of the traverse bar and also the boom suspension, means controllable by an operator on the carriage for traversing the carriage on the traverse bar and for controlling the operation of the shovel on the boom, a hoist bucket, permanent guide rails in the brace structure for the bucket, and temporary guide rail extensions from the permanent rails and extending into the space below the brace structure for guiding the bucket to a location at the bottom of the shaft.

4. Excavating apparatus for sinking shafts in rock and the like, comprising a supporting structure, a traverse bar having adjustable suspension means extending from the supporting structure, the bar being located in the space below said structure and engageable with a side of the shaft, a traversing carriage on the traverse bar, a boom pivoted on the carriage, adjustable suspension

means extending from the structure for suspending the boom at a desired angle with respect to the bottom of the shaft, and means controllable by an operator near the bottom of the shaft for controlling the adjustable suspension means of the traverse bar to control its elevation, the position of the carriage on the traverse bar and the adjustable suspension means of the boom to control its angle.

5. Excavating apparatus for sinking a shaft in rock and the like, comprising a supporting structure, a traverse bar in the shaft, adjustable suspension means from the structure supporting the traverse bar in a position wherein it may engage a side of the shaft, a traversing carriage on the traverse bar, a boom pivoted on the carriage, adjustable suspension means extending from the structure for suspending the boom at a desired angle with respect to the bottom of the shaft and permitting its traverse, and means controllable by an operator near the bottom of the shaft for controlling both suspension means and for controlling the traverse of the carriage on the traverse bar.
10. Excavating apparatus for sinking a shaft in rock or the like, comprising a supporting structure, a boom support in the shaft, adjustable suspension means extending from the supporting structure for locating the boom support adjacent one wall of the shaft and above its bottom, a boom pivoted to the boom support, an adjustable suspension means extending from the supporting structure for suspending the boom at a desired angle above the bottom of the shaft, and means controllable by an operator near the bottom shaft for controlling both adjustable suspension means.
15. Excavating apparatus for sinking a shaft in rock or the like, comprising an elongate suspended support having substantially spaced ends and adapted to be placed parallel to one vertical wall of the shaft, holding elements adapted to react from the shaft to push laterally on the ends of said portable support toward said vertical wall for anchoring the support near its spaced ends,
20. a suspension device for adjusting the position of said suspended element with respect to said wall prior to anchoring, a boom, movable operative elements located on said support between its held ends for moving the boom with respect to the support, said boom being pivoted to said movable operative elements, a dipper arm on the boom, and control elements for the boom and the dipper arm operative from a station movably carried with the movable operative elements, said station being located between said end supports.
25. Excavating apparatus for sinking a shaft in rock or the like, comprising an elongate suspended support having substantially spaced ends and adapted to be placed parallel to one vertical wall of the shaft, holding elements adapted to react from the shaft to push laterally on the ends of said portable support toward said vertical wall for anchoring the support near its spaced ends,
30. a suspension device for adjusting the position of said suspended element with respect to said wall prior to anchoring, a boom, movable operative elements located on said support between its held ends for moving the boom with respect to the support, said boom being pivoted to said movable operative elements, a dipper arm on the boom, and control elements for the boom and the dipper arm operative from a station movably carried with the movable operative elements, said station being located between said end supports.
35. Excavating apparatus for sinking a shaft in rock or the like, comprising an elongate suspended support having substantially spaced ends and adapted to be placed parallel to one vertical wall of the shaft, holding elements adapted to react from the shaft to push laterally on the ends of said portable support toward said vertical wall for anchoring the support near its spaced ends,
40. a suspension device for adjusting the position of said suspended element with respect to said wall prior to anchoring, a boom, movable operative elements located on said support between its held ends for moving the boom with respect to the support, said boom being pivoted to said movable operative elements, a dipper arm on the boom, and control elements for the boom and the dipper arm operative from a station movably carried with the movable operative elements, said station being located between said end supports.
45. Excavating apparatus for sinking a shaft in rock or the like, comprising an elongate suspended support having substantially spaced ends and adapted to be placed parallel to one vertical wall of the shaft, holding elements adapted to react from the shaft to push laterally on the ends of said portable support toward said vertical wall for anchoring the support near its spaced ends,
50. a suspension device for adjusting the position of said suspended element with respect to said wall prior to anchoring, a boom, movable operative elements located on said support between its held ends for moving the boom with respect to the support, said boom being pivoted to said movable operative elements, a dipper arm on the boom, and control elements for the boom and the dipper arm operative from a station movably carried with the movable operative elements, said station being located between said end supports.
55. Excavating apparatus for sinking a shaft in rock or the like, comprising an elongate suspended support having substantially spaced ends and adapted to be placed parallel to one vertical wall of the shaft, holding elements adapted to react from the shaft to push laterally on the ends of said portable support toward said vertical wall for anchoring the support near its spaced ends,
60. a suspension device for adjusting the position of said suspended element with respect to said wall prior to anchoring, a boom, movable operative elements located on said support between its held ends for moving the boom with respect to the support, said boom being pivoted to said movable operative elements, a dipper arm on the boom, and control elements for the boom and the dipper arm operative from a station movably carried with the movable operative elements, said station being located between said end supports.
